UNITED STATES PATENT OFFICE.

CHARLES G. COUGHLAN, OF NEW BRITAIN, CONNECTICUT, ASSIGNOR TO LANDERS, FRARY & CLARK, OF NEW BRITAIN, CONNECTICUT, A CORPORATION OF CONNECTICUT.

CONTROLLING DEVICE FOR ELECTRICALLY-HEATED UTENSILS.

Application filed May 29, 1919. Serial No. 300,620.

To all whom it may concern:

Be it known that I, CHARLES G. COUGHLAN, a citizen of the United States, and a resident of New Britain, in the county 5 of Hartford, State of Connecticut, have invented certain new and useful Improvements in a Controlling Device for Electrically-Heated Utensils, of which the following is a specification.

10 This invention relates to a controlling device for electrically heated utensils and has as its object to provide a unitary structure for detachably connecting the circuit wire or cord to the utensil and controlling 15 the current through the utensil so that the current may be controlled at the point where the cord or circuit wire is connected onto the utensil.

A controlling device constructed in accordance with the present invention is simple and compact in construction, and neat and pleasing in appearance.

The above and other objects of my invention are obtained in the structure described 25 in the following specification and illustrated in the accompanying drawings; and wherein:

Fig. 1 is an elevational view of an electrically heated utensil to which my improved controlling device is attached.

Fig. 2 is a sectional view taken centrally through the controlling device.

Figs. 3 and 4 are inside views of the bottom and top parts respectively of the base 35 portion of the device.

Fig. 5 is an end view with a portion of the base in section.

I have illustrated in Fig. 1 an electrically heated utensil 10, the same being shown 40 more or less conventionally as my improved controlling device is applicable for use in connection with any type of electrically heated utensil. The utensil shown is of the multi-heat type having resistance elements 45 (illustrated diagrammatically in Fig. 5) which transform the current into heat, and these resistance elements have the usual terminals which in the present instance comprise terminal posts 11, three in number as 50 shown by dotted lines, Fig. 5.

My controlling device has a base or body portion constructed of insulating material, such as porcelain, and while this base may

be of any suitable construction, the specific formation thereof being immaterial, I have shown the same, for illustrative purposes, as comprising two parts 12 and 13 secured together by bolts 14 passing through the openings 15 in the parts. Mounted within the base are terminal members which are 60 adapted to be detachably connected to the terminal posts 11 of the heating element of the utensils, and while I have shown these terminals as comprising spring clips 16 spaced similarly to the terminal posts 11 so 65 as to receive the same, it is to be understood that the type of terminals may be varied, any suitable type being applicable which will permit quick and ready attachment and detachment of the controlling device to and from the utensil. It will be seen from the drawing that when attaching the device to the utensil the terminal members 11 and 16 are moved towards each other 70 in a direction at right angles to the face of the base opposed to the utensil.

Carried upon the outer face of the base is a multi-way switch of the rotary type, in the present case, the switch being a four-way one, as the utensil shown has its resistance elements so arranged as to give three heats, as high, medium and low. The switch comprises four posts 17 provided with spring contacts 18, and a spindle 19 carrying two movable contacts such as 80 switch blades 20. The arrangement of the switch parts is such that the switch may be turned into "off", "high", "medium" or 85 "low" positions.

The circuit wires, which as usual are 90 wrapped to form a cord 21, are led into the device through the side of the base. The base is preferably chambered or recessed to provide a space for the connections 15 between the cord, the switch posts 17 and the 95 terminals 16. From the drawings, it will be noted that the spindle 19 is at right angles to the face of the base which abuts against the utensil, and the cord or wires 21 are led into the base in a direction at 100 right angles to the spindle and in parallelism with the inner face of the base and the planes in which the switch blades rotate. With this arrangement, a very compact and simple construction is provided 105 and when attached to a utensil, the button

of the switch does not stand out to the extent that it is unsightly.

It will be seen from the foregoing description that when it is desired to connect 5 the utensil in the line, the controlling device is detachably connected to the utensil by slipping the terminals 16 over the terminal posts 11, and in this position the bottom of the base will lie flat against the side of 10 the utensil. The spring action of the terminal 16 is strong enough to prevent accidental displacement of the controlling device. After the controlling device is applied to the utensil the current is controlled 15 by the rotary switch.

The structure is a unitary one and is of particular advantage as the current may be controlled at the same end of the cord as that at which the cord is connected to the 20 utensil. A person seated before the cooking utensil may attach or detach the device to the utensil and control the current flowing through the utensil without rising from the table or otherwise changing his position.

25 In accordance with the provision of the patent statutes, I have described the principle of operation of my invention, together

with the apparatus which I now consider to represent the best embodiment thereof; but I desire to have it understood that the device 30 shown is only illustrative, and that the invention can be carried out by other means.

I claim as my invention:

A device of the character described comprising a base having an inner abutting face 35 and a chamber in parallelism with said face, a rotary switch upon the opposite outer face of said base and having a spindle at right angles thereto and a switch blade in parallelism therewith, said switch having 40 fixed switch posts on said outer face of said base, a plurality of socket terminals positioned side by side at one end of said base and between said inner and outer faces 45 thereof and extending at right angles to said faces, said socket terminals being offset relative to but in parallelism with said switch spindle, connections within said chamber between said switch post and said socket terminals, and line wires leading 50 through the side of said base into said chamber and connected to certain of said posts.

CHARLES G. COUGHLAN.
